(21) Appl. No.: **29/309,777**

(57) **CLAIM**

(22) Filed: **Oct. 7, 2008**

The ornamental design for a nail clipper, as shown and described.

(30) **Foreign Application Priority Data**

Apr. 11, 2008 (JP) 2008-009353

(51) **LOC (9) Cl.** **28-03**

FIG. 1 is a front perspective view of a nail clipper showing my new design;

(52) **U.S. Cl.** **D28/60**

FIG. 2 is a rear perspective view thereof;

(58) **Field of Classification Search** 30/26-29,

FIG. 3 is a front view thereof;

30/186; D28/56-60; 132/73-75.6

FIG. 4 is a rear view thereof;

See application file for complete search history.

FIG. 5 is a top plan view thereof;

(56) **References Cited**

FIG. 6 is a bottom plan view thereof;

U.S. PATENT DOCUMENTS

FIG. 7 is a right side view thereof;

2,616,436 A * 11/1952 Langley 132/75.5
2006/0075639 A1 * 4/2006 Wong 30/28
2008/0148572 A1 * 6/2008 Samson 30/28

FIG. 8 is a left side view thereof;

FOREIGN PATENT DOCUMENTS

FIG. 9 is a front perspective view thereof showing the article in which the operation lever is opened; and,

JP	S-536499	7/1980
JP	S-536499-001	2/1983
JP	S-602668	6/1983
JP	S-536499-002	1/1984
JP	S-717535	11/1987
JP	S-766988	7/1989
JP	S-787471	5/1990
JP	S-816458	8/1991
JP	S-823099	11/1991

FIG. 10 is a rear perspective view thereof showing the article in which the operation lever is opened.

The broken lines connecting the solid contour lines of the nail clipper represent the bounds of the claim. The remaining broken lines illustrate portions of the article. None of the broken lines form part of the claimed design.
